MOLDED PULP TRAY

Thomas B. Kennedy, Stamford, Conn., assignor to Diamond National Corporation, New York, N.Y., a corporation of Delaware

Filed Jan. 8, 1964, Ser. No. 78,125

Term of patent 14 years

(Cl. D58—12.6)

FIG. 1

FIG. 2

FIG. 3

FIG. 4

FIG. 1 is a top plan view of a molded pulp tray showing my new design;

FIG. 2 is a vertical section taken along the line 2—2 and looking in the direction of the arrows;

FIG. 3 is an enlarged fragmentary view of a portion of the bottom of the tray illustrated in FIG. 1; and

FIG. 4 is a vertical section taken along the line 4—4 of FIG. 3 and looking in the direction of the arrows.

The characteristic feature of my design resides in the bottom surface of the tray, particularly the appearance of the large planar diamond shaped area in relation to the symmetrically disposed network of relatively smaller diamond-shaped inscribed areas substantially covering the inner surface of the tray bottom as shown.

I claim:
The ornamental design for a molded pulp tray, as shown and described.
